TRAY SUPPORTING MEANS

Warren McArthur, Bantam, Conn., assignor, by
mesne assignments, to Reconstruction Finance
Corporation, New York, N. Y., a corporation of
the United States

Application November 16, 1946, Serial No. 710,331

5 Claims. (Cl. 155—127)

1

This invention relates to an article of manufacture, and more particularly to means for supporting a tray or the like.

The apparatus of this invention has wide application and may be advantageously employed in conjunction with various types of seating equipment, and especially with aircraft seats. As will be apparent from the detailed description further along herein, a plurality of tray supporting arms and associated devices are slidably disposed within a hollow support, such as the arm of a chair, and are maintained completely hidden from view at such times as the tray arms are out of active use, due to the action of a detent means. The parts are so arranged that, upon release of the detent means, the tray arms and related devices may be readily protracted with respect to the hollow support, whereupon the arms are pivoted to upright position to receive and support a suitable tray or similar device in convenient location with respect to the occupant of the chair.

It is the primary object of the invention to provide an improved tray support of the character indicated.

The invention has for another object the provision of supporting means for a tray or the like, wherein a plurality of tray arms are adapted to be disposed within a hollow support, such as a hollow arm rest, at such times as they are out of active use.

Another object of the invention is to provide tray supporting means wherein certain of the parts are telescopically arranged with respect to other parts and are adapted to be readily placed into and out of active service.

A further object of the invention is to provide a collapsible tray supporting means capable of performing its intended functions in an effective and trouble-free manner.

The foregoing objects, as well as other objects, together with the advantages obtainable by the practice of this invention, will be understood by persons skilled in the art upon reference to the following detailed description, taken in conjunction with the annexed drawings, that respectively describe and illustrate apparatus embodying a preferred form of the invention.

In the drawings:

Figure 1 is a view in side elevation of a chair having the tray supporting means of this invention operatively associated therewith;

Figure 2 is a view in front elevation of the chair and associated devices shown in Figure 1;

Figure 3 is an enlarged cross-sectional view taken along line 3—3 of Figure 1;

2

Figure 4 is a view taken along line 4—4 of Figure 3;

Figure 5 is an enlarged fragmentary view of a portion of Figure 4;

Figure 6 is a view taken along line 6—6 of Figure 5;

Figures 7 and 8 are views corresponding to Figures 3 and 4, respectively, and show the parts in another relative position;

Figure 9 is an enlarged cross-sectional view taken along line 9—9 of Figure 7;

Figure 10 is an enlarged cross-sectional view taken along line 10—10 of Figure 7;

Figure 11 is an enlarged cross-sectional view taken along line 11—11 of Figure 7; and

Figure 12 is an enlarged cross-sectional view taken along line 12—12 of Figure 7.

Referring now to the drawings, and more particularly to Figures 1 and 2, there is illustrated therein a chair 15 that comprises a pair of side frames 16, preferably of welded tubular construction, each of which consists of a front leg 17, a rear leg 18, a side stretcher 19 and a hollow arm rest or support 20. Side frames 16 are maintained in spaced-apart parallel relation by suitable devices including a front stretcher 21. The chair preferably includes a cushioned seat 22 and a cushioned back 23 of any desired construction.

Each hollow support 20 is preferably formed from a section of square tubing having a bottom wall 25, a top wall 26, and side walls 27. A pair of apertures 30 for receiving a locking pin, that will be hereinafter described, are formed in one of side walls 27. An angle bracket 31, secured to bottom wall 25 by a rivet 32 (Figure 8), serves as a closure for the rear end of hollow support 20 and also as a support for a coil spring 33 that is secured to the vertical flange of bracket 31 by a bolt 34 and a nut 35, and that is positioned within hollow support 20 in spaced relation to its defining walls. Wholly within hollow support 20 and attached to bottom wall 25 by a series of rivets 36 is a C-shaped track 37.

A generally channel-shaped member 40 is telescopically arranged with respect to hollow support 20. Member 40 consists of a web 41, side flanges 42, an integral rear end plate 43, and a front end plate or escutcheon 44 having a ring insert 45. Secured to the under surface of web 41 by rivets 46 is a channel runner 47 adapted to be inserted in and slidably along track 37.

Members 40 is adapted to be maintained in the fully telescoped position with respect to hollow support 20 by a detent means that will now be

described. This detent means includes a bell crank 50 that is pivotal about a bolt 51, extending upwardly through web 41, and that is secured in spaced relation to member 40 by a spacer sleeve 52 and a nut 53 (Figure 10). One end of bell crank 50 is pivotally connected by a pin 54 to the bifurcated end portion of a detent or locking pin 55 that is movable through a side flange 42 and that is provided with a shoulder 56 (Figure 11). With the parts arranged in the relative position shown in Figures 7 and 11, the free end of pin 55 is in registration with rearward aperture 30. A locking bar 57 is connected to the other end of bell crank 50 by a pivot pin 58. The forward end portion of bar 57 is bent upwardly and carries a button release 60 that projects through and beyond ring insert 45. A helical spring 61 is connected at one end to pivot pin 58 and at its other end to web 41. This spring is stressed in tension at all times and, as viewed in Figure 7, normally urges bar 57 toward the left and detent pin 55 upwardly and into registration with an aperture 30, as allowed by shoulder 56.

Each member 40 carries a pair of tray supporting arms 65 that will next be described. These arms are best shown in Figures 4, 5 and 6, and each is machined at one end to form a pair of parallel fingers 66 and a shoulder 67. The major portion of each arm 65 is of channel configuration and includes a web 68 and flanges 69 that are beveled at their free ends, as indicated at 70 (Figure 5). The flanges 69 extend beyond web 68 so as to provide a recess 71 to accommodate locking bar 57 when each arm 65 is in upstanding position. A pin 72 extends across member 40 and is journaled in flanges 42. Arm 65 is pivotal about pin 72 directly adjacent beveled edges 70 and is spaced from flanges 42 by spacer rings 73. A sleeve 74 mounted on pin 72 is secured thereto by a cotter pin 75 (Figures 5 and 6) to prevent axial movement of pin 72. Upon removal of cotter pin 75, pin 72 may be withdrawn from member 40 to permit arm 65 to be disconnected from member 40. A spring 76 is coiled about sleeve 74 and bears against web 41 of member 40 and web 68 of arm 65, respectively, to normally swing the arms about their respective pivotal connections to the corresponding positions illustrated in Figures 1 and 4, at which time the lower extremity of each arm flange 69 bears against the upper surface of web 41 to limit pivotal movement of each arm and maintain the arms in upstanding, substantially parallel relation.

The above described apparatus is adapted to support a tray 80 that is formed with a continuous recess 81 and that is provided with suitable openings 82. With the parts assembled as shown in Figures 1 and 2, fingers 66 are received in tray openings 82 and the tray rests on shoulders 67 of arms 65.

For the purpose of briefly describing the operation of this invention, reference is first had to Figures 7 and 8 wherein the parts are illustrated in the relative position when they are out of service. At such times, member 40 is fully telescoped within hollow support 20, bearing against spring 33 which is stressed in compression, arms 65 are swung about pivot pins 72 and folded within member 40, fingers 66 contacting the under surface of top wall 26 due to the action of springs 76. Detent pin 55 registers with rearwardmost aperture 30 to maintain support 40 and associated devices in telescoped position against the action of spring 33. Escutcheon 44 covers the forward end of hollow support 20, presenting a

neat, finished appearance. It will thus be seen that the tray supporting structure is hidden from view when not in active service.

When release button 60 is pressed inwardly or toward the right, as viewed in Figure 8, locking bar 57 is correspondingly moved in the same direction, imparting clockwise pivotal movement to bell crank 50, as viewed in Figure 7, and placing detent pin 55 out of registration with aperture 30. Member 40 and the devices secured thereto are then protracted forwardly with respect to hollow support 20 by spring 33. Member 40 may be extended fully with respect to the hollow support by spring 33 or may be partially extended by the action of this spring, further protraction being effected manually. In either event, each arm 65, as it moves beyond the open end of support 20, is swung to the upright position illustrated in Figures 1, 2 and 4 due to the action of its spring 76. Member 40 is prevented from being accidentally completely withdrawn from support 20 by detent pin 55 which automatically registers with forward aperture 30 (Figure 3) when the member has been moved to normal, fully extended position with respect to the hollow support.

To return the parts from their relative position shown in Figure 4 to that illustrated in Figure 8, the detent means is manually actuated to place detent pin 55 out of registration with forward aperture 30, and member 40 is moved inwardly with respect to support 20. Continued inward movement of member 40 brings web 68 of rearward arm 65 in contact with the front edge 35 of top wall 26, whereupon this arm is swung in a counter-clockwise direction (Figure 4) against the action of its spring 76. Forward arm 65 is manually swung in a clockwise direction (Figure 4) against the action of its spring 76 and held in downward position until its fingers 66 are disposed in the forward end of support 20. Further continued movement of member 40 effects compression of spring 33 and permits locking engagement of detent pin 55 with rearward aperture 30.

From the foregoing, it is believed that the construction, operation, and advantages of my present invention will be readily comprehended by persons skilled in the art. It is to be clearly understood, however, that various changes in the apparatus set forth above may be made without departing from the scope of the invention, it being intended that all matter contained in the description or shown in the drawings shall be interpreted as illustrative only and not in a limiting sense.

I claim:

1. In supporting means for a tray or the like, a hollow support, a member telescopically mounted in the support, detent means for controlling sliding movement of the member with respect to the support, a first arm pivotally connected proximate one end to the member, a second arm pivotally connected proximate one end to the member, the axes of the pivotal connections being substantially parallel, said arms being disposed in the support with their other ends projecting toward each other, means for imparting movement to the arms about their respective pivotal connections upon release of the detent means and predetermined protracted movement of the member with respect to the support, and means for limiting said movement of each arm about its pivotal connection.
2. In supporting means for a tray or the like,

a hollow support, a member telescopically mounted in the support, detent means for controlling sliding movement of the member with respect to the support, a first arm pivotally connected proximate one end to the member, a second arm pivotally connected proximate one end to the member, the axes of the pivotal connections being substantially parallel to each other and substantially normal to the path of travel of the member with respect to the support, said arms being disposed in the support with their other ends projecting toward each other, and resilient means for imparting movement to the arms about their respective pivotal connections and for maintaining the arms in parallel relationship upon release of the detent means and predetermined protracted movement of the member with respect to the support.

3. In supporting means for a tray or the like, a hollow support having a plurality of apertures, a member telescopically mounted in the support, a detent pin carried by the member and registering with one of the apertures to control sliding movement of the member with respect to the support, spring-urged means for maintaining the pin in registration with said one of the apertures, release means operable from the exterior of the support for placing the pin out of such registration against the action of the spring-urged means, a first arm pivotally connected proximate one end to the member, a second arm pivotally connected proximate one end to the member, the axes of said pivotal connections being parallel, said arms being disposed in the support with their other ends projecting toward each other, and means for imparting movement to the arms about their respective pivotal connections upon actuation of the release means and predetermined protracted movement of the member with respect to the support.

4. In supporting means for a tray or the like, a hollow support having a plurality of apertures, a member telescopically mounted in the support, a detent pin carried by the member and registering with one of the apertures to control sliding movement of the member with respect to the support, spring-urged means for maintaining the pin in registration with said one of the apertures, release means operable from the exterior of the support for placing the pin out of such registration against the action of the spring-urged means, a first arm pivotally connected proximate one end to the member, a second arm pivotally connected proximate one end to the member, the axes of said pivotal connections being parallel, said arms being disposed in the sup-

port with their other ends projecting toward each other, and resilient means for imparting movement to the arms about their respective pivotal connections and for maintaining the arms in parallel relationship upon actuation of the release means and predetermined protracted movement of the member with respect to the support, said detent pin normally registering with another of said apertures to limit protracted movement of the member with respect to the support.

5. In supporting means for a tray or the like, a hollow support having a plurality of apertures, a member telescopically mounted in the support, a detent pin carried by the member and registering with one of the apertures to control sliding movement of the member with respect to the support, spring-urged means for maintaining the pin in registration with said one of the apertures, release means operable from the exterior of the support for placing the pin out of such registration against the action of the spring-urged means, means for effecting protraction of the member upon actuation of the release means, a first arm pivotally connected proximate one end to the member, a second arm pivotally connected proximate one end to the member, the axes of said pivotal connections being parallel, said arms being disposed in the support with their other ends projecting toward each other, and resilient means for imparting movement to the arms about their respective pivotal connections and for maintaining the arms in parallel relationship upon actuation of the release means and predetermined protracted movement of the member with respect to the support, said detent pin normally registering with another of said apertures to limit protracted movement of the member with respect to the support.
